UNITED STATES PATENT OFFICE.

CHARLES ALBERT BRUNNER, OF LEVALLOIS PERRET, FRANCE.

DISTRIBUTING DEVICE FOR STEAM OR AIR ENGINES.

SPECIFICATION forming part of Letters Patent No. 716,664, dated December 23, 1902.

Application filed July 18, 1901. Serial No. 68,272. (No model.)

To all whom it may concern:

Be it known that I, CHARLES ALBERT BRUNNER, builder, residing in Levallois Perret, Seine, France, have invented certain new and useful Improvements in Pumping-Engines, of which the following is a full, clear, and exact description and for which I have applied for Letters Patent in France, dated December 15, 1900, No. 306,295.

10 This invention consists of an improved construction of valve mechanism for steam or compressed-air engines having reciprocating pistons, especially for the actuation of pumps by direct connection.

15 The accompanying drawings illustrate a steam-engine fitted with the invention and driving a lubricating-pump.

Figure 1 is a view of the whole in elevation. Fig. 2 is an elevation of the same viewed at right angle, but showing only the steam-cylinder driving the pump. Fig. 3 is a horizontal section on line A B of Fig. 1. Fig. 4 is a corresponding plan view of Fig. 2. Fig. 5 is a view of the whole in vertical section on line C D of Fig. 3. Fig. 6 is a vertical section of a double-pump arrangement.

The steam-engine comprises a cylinder 1, in which works a piston 2, of which the piston-rod 3, suitably guided, as usual, in a 30 stuffing-box 4, is extended and connected to the piston or plunger of the pump, as will be presently described. The supply of steam to this cylinder is effected by the following mechanism: At the ends of the piston-stroke are two ports 5, which deliver first on to the internal surface of a truncated conical chamber 6, arranged within a lump upon the cylinder. Into this truncated conical chamber 6 there is inserted and fits with slight friction, 35 as in a valve-seat, a truncated plug 7, fixed axially upon a shaft 8, suitably supported and journaled in a stuffing-box 9. In plug 7 are formed the following different passages: Two ports 10 10 lead from a common opening 11 upon the small base of the cone and to the truncated wall at two points 12 12. Two other ports 13 13, independent one of the other, deliver at 14 14 to the larger base of the cone and also at 15 15 to the conical surface. The construction is clearly shown in Figs. 3 and 5. In the aforesaid pump, in which the said chamber or seat is formed, is also

provided a passage 16, which delivers against the small base of the cone opposite to the opening 11. The escape of steam takes place 55 through this passage 16. The steam is admitted through an inlet 17, opening into the seat 6 below the larger base of the truncated cone-plug 7. The shaft 8 of the plug or valve 7 is provided at its extremity with a head in 60 the form of a sector or cam 18, secured thereto. Upon this end of the shaft 8 is loosely journaled a frame of special construction. This frame consists of two arcs of a circle 19 19, of which the cords are parallel and which 65 are connected by two rectilinear portions 20 20. To one of the arcs is joined a part 20^a, journaled upon shaft 8. To this part 20^a is secured an arm 21, projecting upwardly and upon which is fixed an adjustable weight 22. 70

The rod 3 of the piston 2 is connected, by means of a cross-piece 23, to a rod 24, which is parallel thereto and which is thus rendered integral therewith. This rod 24 is guided at 25 in the supporting-beam of the pump and 75 at 26 and 27 in the upper and lower plates of the cylinder 1. It is provided at its lower part with a projection or stop 28, which passes through the hollow of the frame 19 19 20 20.

The oil-pump is arranged above the steam-cylinder and axially thereof. The body of the pump 29 is fixed to a plate 30, connected to the steam-cylinder by three pillars 31 31 31. The plunger-piston 32 is arranged upon the upper end of the rod 3 of the piston 2 of 85 the steam-cylinder. It is guided in a stuffing-box 33. The entrance of oil is effected through a pipe 34 and valve 35, and the exit is made through a force-valve 36 and pipe 37.

The working of this apparatus is as follows: 90 The distributing mechanism effects the admission and exhaust by the partial and alternating rotation of the rotary valve 7. These movements of alternating rotation are effected by the rectilinear movement of the projection 28 in the frame 20 21, and this projection 28 is secured to the rod 24, which is itself solid with the rod 3 of the piston. This projection 28 thus effects a rectilinear reciprocating movement within the aforesaid frame 95 20 20 21 21. This movement determines the oscillation of this frame. The latter at its portion 20^a acts alternately on the two ends of the cam 18, integral with the shaft 8 and

the circular valve. To this is thus imparted a partial rotation rapidly alternating in opposite directions, by means of which at each of its extreme positions a port 10 coincides with one of the ports 5, so as to effect the exhaust, while a port 13 coincides with the other port 5 in order to effect the admission of steam.

The proper fit or joint of the rotary valve 10 with the wall of the hollow wherein it moves is insured by the same pressure of the steam which acts upon the larger base of the valve. The limits of the stroke of the counterweighted arm 21, and consequently of the frame 15 and of the valve, are determined by two abutments or stops 21^a, formed upon the framework or the outside of the cylinder.

In the case of two superposed pumps the plunger-piston of the lower pump is extended by means of a rod which forms the plunger-piston of the second pump. Fig. 6 shows such an arrangement in section.

I do not limit myself strictly to the details of construction of the apparatus shown on the drawings, and I may make therein various alterations and constructional modifications which do not change the essential arrangements set forth.

Having thus described my invention, what

I claim as such, and desire to secure by Letters Patent, is—

1. A steam-engine having a cylinder, a reciprocating piston, a valve-chamber, a valve mechanism comprising the combination of a rotary valve, coöperating parts between the valve and cylinder and a spindle for the valve, a sector-head on the spindle, a frame journaled on said spindle, a weight on the frame, and a projection on the reciprocating piston to act on the frame, substantially as described. 40

2. A valve mechanism for a steam-engine having a reciprocating piston, said mechanism comprising the combination of a valve-chamber, a rotary valve in the form of a truncated cone and having ports 10, 11, 12, 13, 14, 45 and 15, corresponding passages in the casing, a spindle on the valve, and a sector-head on the spindle, with a frame journaled on the spindle, and a projection on the reciprocating piston to act on said frame, substantially as 50 described.

In testimony whereof I have signed my name to this specification in the presence of two subscribing witnesses.

CHARLES ALBERT BRUNNER.
